John W. Ramsey, Inventor
By his Attorney, G. B. Brock

UNITED STATES PATENT OFFICE.

JOHN W. RAMSEY, OF BEAVER FALLS, PENNSYLVANIA, ASSIGNOR OF ONE-HALF TO JOHN CORBUS, OF SAME PLACE.

FLUID-REGULATING VALVE.

SPECIFICATION forming part of Letters Patent No. 340,458, dated April 20, 1886.

Application filed February 13, 1886. Serial No. 191,858. (No m. del.)

To all whom it may concern:

Be it known that I, JOHN W. RAMSEY, a citizen of the United States, residing at Beaver Falls, in the county of Beaver and State of Pennsylvania, have invented certain new and useful Improvements in Fluid-Pressure-Regulating Valves, of which the following is a specification, reference being had therein to the accompanying drawings.

10 My present invention relates to fluid-pressure regulators.

The drawings represent, Figure 1, a vertical sectional view of a device to which I have applied my improvements, and Fig. 2 a plan view of the same.

15 The object of the improvement consists in taking gas, water, steam, or other vapor from a high-pressure service-pipe and distributing it at any given reduced pressure, according to 20 the needs of the service.

With the above objects in view my invention consists in the following construction and arrangement, which will first be fully set forth and described, and the features of novelty believed to be new then set forth in the claims.

25 Referring to the drawings and to the same parts by the same figures of reference, 1 represents the cylinder or valve to which the high-pressure service-pipe is connected at the opening 2. Cylinder 3 is the equalizing pressure-reducing cylinder.

30 4 6 is a plunger cylindrical cut-off. It is made in two parts, united by a series of tie-pieces, 5. These tie-pieces 5 on the inner side of the cut-off cylinder are preferably four in number, disposed at equal distances apart, and connect the two parts of the cut-off rigidly. The head 7 of the upper part, 6, is closed, and the lower part, 4, of the cylindrical plunger is 35 open.

40 8 is the valve-stem of the plunger 4 6. It passes through the head 9 of the cylinder 1 by means of a fluid-tight stuffing-box, 10.

45 11 is an annular fluid-passage cast or formed with the cylinder 1. It communicates with the interior of the cylinder 1 throughout the circumference of the latter. The opening 2 for the high-pressure pipe registers with the passage 11. Cylinder 1 is preferably formed 50 with the head 12 at its lower end, integral

therewith, while the upper head, 9, is secured by a flanged joint and screw-bolts.

Secured to the upper head, 9, or east therewith is a pivotal joint, 13, in which is pivoted a link, 14.

55 15 is a lever arm or rod, pivoted at one end to the link 14 and at the other to the hollow plunger-stem 17. Lever 15 is connected to the plunger-valve stem 8 of cut-off 4 6, between link 14 and stem 17.

60 16 is a sliding weight traversing the lever-arm 15, and serves to regulate the pressure in the distributing-pipe at any reduced head desired.

18 is a hollow plunger of cylindrical form 65 adapted to fit tightly within the open-ended cylinder 3. Plunger 18 has a fluid-tight head at its upper end, where the stem 17 is secured, the lower end only being open.

19 is the distributing low-pressure pipe. It 70 is connected with the cylinders 1 and 3, and from thence leads to the source of supply. A T-connection, 20, and branch pipe 21 form the communication with cylinder 3.

Secured to branch pipe 21, or to the lower 75 head of cylinder 3, is an enlarged pipe, 22, having an open top, and extending nearly the length of cylinder 3. Pipe 22 is nearly the diameter of plunger-cylinder 18. Cylinder 3 has a series of annular recesses, 23, or corrugations.

80 Exteriorly to pipe 22, but within the cylinder 3, is an annular space intended for the movement of the plunger-cylinder 18 therein, and also for receiving a quantity of mercury, 85 oil, or other suitable liquid. The liquid stands in the cylinder up to the annular recesses 23, wherein it serves as an effective packing for the plunger, and prevents the escape of the fluid which is being regulated. The mercury or oil also fills the space between the exterior of pipe 22 and interior of plunger 18, and performs the same office—that is, prevents the escape of the regulated fluid.

85 If desirable, pipe 22 may be dispensed with and some other known form of packing may be given plunger 18 other than fluid mercury or oil.

90 Lever 15 is shown passing through a knife-edged slot in valve-stem 8. Said stem may be 100

simply pivoted to the lever 15, if desired, and plunger-stem 17 may be provided with a knife-edged slot to allow the necessary endwise movement of lever 15.

5 24 is a slot in lever 15 to allow a similar movement. The pivotal pin of stem 17 passes through the slot.

In operation (supposing the position of the operative parts to be as represented in Fig. 1) 10 the pressure from the source of supply entering at opening 2 passes into and around the annular passage 11. From thence it passes between the two parts of the valve 4 6. Head 7 of this valve prevents the escape of fluid in 15 an upward direction. It therefore passes through the distributing pipe 19 and pipe 21, where it exerts its force against the head of hollow plunger 18. The pressure thus exerted against the plunger 18 and valve 4 6 causes 20 them both to move upwardly, when the mid-opening of the latter gradually cuts off the high-pressure service by passing gradually beyond the annular passage 11 in the cylinder 1. Upon such movement taking place the pressure 25 in hollow plunger 18 is gradually lessened, and ceases to exert a preponderance of motion before the valve 4 6 cuts the supply entirely off. Weight 16 is slid along to such 30 position upon the lever-arm 15 as will secure the regulation of the supply at any reduced pressure which may be desired.

Having described my invention, what I claim as new, and desire to secure by Letters Patent, is—

35 1. A cylinder having an annular opening, and a tubular valve or cut-off located in the

cylinder having an annular opening therein, and an imperforate head against which the steam-pressure is exerted, in combination with a plunger-cylinder containing the plunger, lever-connections between the valve and plunger, and pipe-connections between the same, substantially as set forth. 40

2. A fluid-pressure pipe, an automatic cut-off valve located therein, an exterior corrugated cylinder, an interior cylinder fastened thereto, a liquid arranged between the two cylinders, and a piston-plunger working in the exterior cylinder, with lever-connections between it and the cut-off valve, the whole in 45 combination, essentially as set forth.

3. In a fluid-pressure regulator, a valve-chamber, a tubular valve located in said chamber having an imperforate head at one end and an open head at the other, and steam-ports in 50 both the chamber and valve, in combination with a cylinder having a piston, and lever and pipe connections between the same, as specified.

4. A fluid-pressure pipe, an automatic cut-off valve located therein, a cylinder containing a liquid, a tubular plunger having a closed head at one end working in the cylinder and liquid, and lever and pipe connections between said cylinder and the cut-off valve, all 55 in combination, as set forth.

In testimony whereof I affix my signature in presence of two witnesses.

JOHN W. RAMSEY.
